Samuel H. Manscire, of Albany, N.Y.

Letter Patent No. 2520 - Dated May 15, 1866.

Design for the Plates of a Parlor Stove.

The schedule referred to in these letters Patent and writing, parts, etc., are

as follows:

Be it known that Samuel Manscire, of the
City and County of Albany and State of New York, have invented or pro-
duced a new and original design for the plates of a Parlor Heating Stove,
and I do hereby declare that the following is a full and exact description
of the same, reference being made to the accompanying photographs:

A represents the design for door.

B represents the design for rear.

C represents the design for side.

D represents the design for top.

E represents the design for bottom.

F represents the design for section of front.

G represents the design for side.

Together forming plates for Parlor Heating Stove, Volcani.

It is my desire to secure by letter Patent the design

for plates of a parlor stove as shown and described.

Witness,

Geo. D. Burton,

Jacob Greig
